UNITED STATES PATENT OFFICE.

JEAN B. E. H. CÔTÉ, OF WEYMOUTH, MASSACHUSETTS.

TOOL-HOLDER.

1,326,254.

Specification of Letters Patent. Patented Dec. 30, 1919.

Application filed February 1, 1918. Serial No. 214,929.

To all whom it may concern:

Be it known that I, JEAN B. E. H. CÔTÉ, a citizen of United States, residing at Weymouth, in the county of Norfolk and State of Massachusetts, have invented certain new and useful Improvements in Tool Holders; and I do hereby declare the following to be a full, clear, and exact description of the invention, such as will enable others skilled in the art to which it appertains to make and use the same.

This invention relates to a tool holder designed for holding the cutting tools used on planers, shapers or similar metal working machines, and the primary object of the invention is to provide a holder for carrying two cutting tools arranged in opposite relation to each other whereby the tool will make a cut upon both strokes of the plates of the planer, thereby enabling the operator of the machine to cut practically twice the metal from a casting upon each stroke of the planer plates and eliminating the dead back stroke of the plates.

More specifically, this invention comprehends a tool holder including a head provided with a recess in which is pivotally mounted a pair of spring controlled tool holding sockets, which adjustably and removably support the metal cutting tools which tools are arranged in opposed relation to each other, one of them being longer than the other, while the short tool has its cutting edge placed substantially one eighth of an inch ahead of the cutting edge of the long tool so as to place a first cut on the metal while the long tool will take a second or following cut in the path of the cut of the short tool, upon the reverse stroke of the planer plates.

With the foregoing and other objects in view this invention consists in such novel features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views and in which:

Figure 1 is a perspective view of the improved tool holder.

Fig. 2 is a side elevation of the tool holder having the inclosing sides or plates removed to expose the interior of the head.

Fig. 3 is a section through the head.

Fig. 4 is a transverse section through the head taken on the line 4—4 of Fig. 2.

Fig. 5 is a section on the line 5—5 of Fig. 2.

Fig. 6 is a detail perspective view of one of the pivoted tool holding sockets.

Fig. 7 is a fragmentary enlarged section through a part of one of the tool holding sockets illustrating the manner of connecting the springs thereto and

Fig. 8 is a detail view of the wrench used for loosening the tools in the sockets.

Referring more particularly to the drawings, 1 designates the main body of the tool head, which includes a rectangular tool carrying portion 2 having a shank 3 formed thereon which is adapted to be seated in the chuck or tool carrying element of a planer, shaper or analogous machine.

The rectangular head 2 is provided with a recess 4 formed therein which communicates with its outer end or edge and one side thereof, as shown in Fig. 2 of the drawings.

Said recess 4 is divided substantially equidistance from its ends by a substantially triangular shaped extension 5 which projects inwardly from the inner wall of the recess, and has its apex positioned at the transverse center and substantially at the longitudinal center of the recess so that the sides of the extension will form stops for limiting the inward pivotal movement of the tool carrying sockets 6 and 7. The tool carrying sockets 6 and 7 are pivotally mounted within the recess 4, upon bolts 9 which extend through the tool socket members 6 and 7 and have their inner ends threaded into the head 2 as shown at 10 in Fig. 5 of the drawings. The inner wall of the recess 4, outwardly from the sides of the extension 5 is curved, as shown at 11 to provide a bearing for the inner end of the tool carrying members or elements 6 and 7. The sides of the members 6 and 7 slightly diverge from their curved ends 12 and the outer ends of these members are beveled as shown at 13, outwardly of the tool receiving sockets 14 thereof. The sockets 14 receive ordinary metal cutting tools 15 and 16 respectively which have their cutting edges shaped to properly engage or cut cast iron or similar metal such as is worked upon a planer, shaper or the like. The tool carrying elements 6 and 7 are provided with set screws 18. The set screws 18 engage the

inner wall of the recess 4, outwardly from the sides of the extension 5 is curved, as shown at 11 to provide a bearing for the inner end of the tool carrying members or elements 6 and 7. The sides of the members 6 and 7 slightly diverge from their curved ends 12 and the outer ends of these members are beveled as shown at 13, outwardly of the tool receiving sockets 14 thereof. The sockets 14 receive ordinary metal cutting tools 15 and 16 respectively which have their cutting edges shaped to properly engage or cut cast iron or similar metal such as is worked upon a planer, shaper or the like. The tool carrying elements 6 and 7 are provided with set screws 18. The set screws 18 engage the

tools 15 and 16 for holding these tools rigidly in place in the sockets 14 and the set screws are tightened or loosened by the employment of the wrench 19 illustrated in 5 Fig. 8 of the drawings.

The tool carrying elements 6 and 7 are provided with recesses 20 and 21 respectively, formed in their facing sides in which recesses the ends of the spiral springs 22 extend. The spring 22 yieldably holds the tool carrying elements 6 and 7 in spread position and with their outer sides in engagement with the end walls of the recess 4 against which the outer edges of the tool carrying 10 elements abut when the tool carried thereby is cutting and it further permits the tool which is running idle to pass freely over the casting or metal being worked.

A plate 24 is attached to the side of the 20 head 2 into which the recess 4 opens, and this plate forms a closure for the recess. The plate 24 is attached to the head 2 by suitable bolts 25 so that it may be readily removed if desired. The plate 24 is provided 25 with a plurality of openings 26 which align with the openings 27 formed in the set screws 18, so that the wrench 19 may be inserted through the openings 26 and into the openings of the set screws 18 for tightening 30 or loosening the set screws to permit the removal of the tools 15 and 16.

A relatively thin plate 27 is mounted over the end of the head 2 and forms a closure for the greater portion of the recess 4 which 35 opens into the end of the head 2. The plate 27 is provided with a rectangular slot 28 formed centrally therein through which the tools 15 and 16 pass during the pivotal movement of the tool carrying elements 6 and 7.

In the operation of the improved tool carrying head, or tool holder, the cutting tool 15 is shorter than the cutting 16 and it has its cutting edge positioned substantially 45 one eighth of an inch ahead of the cutting edge of the tool 16 and in starting a cut upon a piece of work, the tool 16 is placed

nearest the rail of the planer so that it will take the first cut during the forward or outward stroke of the platen of the planer. 50 Upon the return stroke of the planer platen, the tool 16 will ride over the work, owing to the pivotal connection of element 17 which carries the tool and the tool 15 will take the cut from the metal during which the outer 55 edge of the element 6 will be forced into firm abutting engagement with one end of the recess 4, holding the tool 15 rigid. Then upon the second outward stroke of the planer platen, the tool 16 will take a second cut 60 over the portion which was previously cut by the tool 15, whereby with the improved tool holder it will be possible to cut substantially twice the amount of metal from a casting upon one complete movement of 65 the tool head across the work being cut and resulting in a consequent saving of time and power.

Having thus fully described the invention what is claimed is:

An apparatus of the character set forth including a head having a recess provided with inwardly tapered end walls and a rear wall provided with a pair of rounded surfaces, work holding elements pivoted within said recesses and having their rear end portions rounded and abutting the rounded surfaces of the rear wall of the recess, a tapered shoulder disposed between said work holding elements for limiting the inward 75 pivotal movement of the same, the outer longitudinal sides of said work holding elements being tapered and adapted to squarely abut the adjacent tapered end walls of the recess, and spring means normally retaining the work holding elements in engagement with the adjacent end walls of the recess.

In testimony whereof I affix my signature in presence of two witnesses.

JEAN B. E. H. CÔTÉ.
